UNITED STATES PATENT OFFICE.

WILLIAM H. BECKER, OF GARALD, MISSOURI.

LID-CLAMP FOR CASES OR CRATES.

1,286,503.

Specification of Letters Patent.

Patented Dec. 3, 1918.

Application filed December 29, 1916. Serial No. 139,666.

To all whom it may concern:

Be it known that I, WILLIAM H. BECKER, a citizen of the United States, residing at Garald, in the county of Franklin, State of 5 Missouri, have invented a new and useful Lid-Clamp for Cases or Crates; and I do hereby declare the following to be a full, clear, and exact description of the invention, such as will enable others skilled in the art 10 to which it appertains to make and use the same.

This invention relates to a new and useful lid or cover clamp, and one of the objects 15 of the invention is to provide a simple and efficient device of this kind, particularly designed for use in connection with egg cases, crates and the like.

A further object of the invention is to 20 provide a clamp consisting of a single piece of spring wire material bent to form a loop, the sides of which having shoulders to engage under a staple, while the terminals of the sides terminate in means to engage over a cleat of the lid or cover of the box or crate, 25 to hold the lid in place.

In practical fields, the details of construction may necessitate alterations falling within the scope of what is claimed.

The invention comprises further features 30 and combinations of parts, as hereinafter set forth, shown in the drawings and claimed.

In the drawings:—

Figure 1 is a view in perspective of a suitable egg case or crate or box, showing the 35 improved lid or cover clamp applied.

Fig. 2 is a view in perspective of the clamp detached.

Fig. 3 is a sectional view on line 3—3 of Fig. 1.

Referring more especially to the drawings, 40 1 designates a suitable box, crate or case, in which any suitable commodity may be shipped and provided with a lid or cover 2. Secured to the upper face of the lid 2 adjacent its ends by means of suitable rivets or the like 3 are cleats 4. Each cleat on its upper surface adjacent each end, and on the side edges of said cleats, grooves or recesses 5 are formed. The outer faces of the upper 45 end cleats 6 of the body of the box or crate are provided with vertical recesses 7, in which the side arms of the lid fastener or clamp engage. However, the recesses or grooves 7 do not extend fully to the lower 50 edge of each cleat 6, hence, shoulders 8 are formed. Each lid fastener or clamp 9 is

constructed from a single length of spring wire bent to form a loop 10, the side arms 11 of which are bent to form the shoulders or outwardly extending portions 12, while 60 the portions of said arms above the shoulders engage and extend vertically of the grooves or recesses 7, and also the grooves of the outer side edge of the cleat or strip 4. The upper portions of the arms 11 of each clamp 65 or fastener are bent at 13 to form the parts 14, which extend laterally and engage the grooves of the upper face of the cleat 4. These portions 14, at their extremities, are bent at 15 to form the lugs 16, which engage 70 the portions 17 of the grooves or recesses 5 of the inner edge of the cleat 4. Staples 18 arch over the sides or arms of the loop of the fastener or clamp, immediately adjacent the shoulders 12, thereby holding the arms 75 11 in the recesses or grooves 7 and the lateral portions and the lugs 16 in the grooves 5, thereby holding the lid or cover clamped to the body of the box or crate securely. When first packing the crate or box for shipment, the clamp is then initially applied.

For instance the cover is placed to close the 80 crate or box, then the clamp is arranged so that the parts 11 14 and 16 will engage the portion adjoining the grooves or recesses 5 85 and 7, whereby the loop 10 will contact with the cleat 6. The staple 18 is then arranged to straddle the arms 11 adjacent the bends between the arms 11 and the portions 12. The staple is then driven home. In order to remove the cover, the parts 14 of each clamp 90 are sprung upwardly and outwardly whereby the cover 2 may be slid or moved transversely of the box or crate. In order to return the cover in closed position with the 95 box or crate, it is the design to slide the cover, so that the cleats 4 may engage under the parts 14, until the arms 11, the parts 14 and 16 will spring into their respective adjoining grooves or recesses 5 and 7 in which 100 case the cover will be held securely in place.

The invention having been set forth, what is claimed as new and useful is:—

The combination with cleats on the adjacent right angle faces of a top and side of a 105 case, of parallel grooves formed in three of the contiguous outer faces of the cleat of the top, the outer face of the side cleat having parallel grooves which align with the first grooves, a fastener being constructed 110 from a single length of spring wire bent upon itself to form a U-shaped loop, the

transverse part of the loop engaging the outer face of the side cleat, the arms of the loop being disposed upwardly and outwardly and bent inwardly and having vertical parts 5 engaging the grooves of the outer face of the side cleat, the upper ends of the vertical parts terminating in right angle parallel portions terminating in downwardly extending hooks, the upper portions of the vertical 10 parts and the right angle parallel portions and the downwardly extending hooks adapted to engage the grooves of the three con-

tiguous outer faces of the top cleat, and a staple arching the arms of the loop where they are bent inwardly toward the side cleat 15 and piercing the side cleat to secure the fastener in place.

In testimony whereof I have signed my name to this specification in the presence of two subscribing witnesses.

WILLIAM H. BECKER.
